(57) **CLAIM**

The ornamental design for a container for metal coil, as shown and described.

DESCRIPTION

FIG. 1 is a perspective view of a container for metal coil showing our new design;

1 Claim, 10 Drawing Sheets

FIG. 2 is a front view of the container for metal coil;

FIG. 3 is a rear view of the container for metal coil;

FIG. 4 is a top elevational view of the container for metal coil;

FIG. 5 is a bottom view of the container for metal coil;

FIG. 6 is a left side view of the container for metal coil;

FIG. 7 is a right side view of the container for metal coil;

FIG. 8 is a perspective view of a second embodiment of a container for metal coil;

FIG. 9 is a front view of the second embodiment of a container for metal coil;

FIG. 10 is a rear view of the second embodiment of a container for metal coil;

FIG. 11 is a top elevational view of the second embodiment of a container for metal coil;

FIG. 12 is a bottom view of the second embodiment of a container for metal coil;

FIG. 13 is a left side view of the second embodiment of a container for metal coil;

FIG. 14 is a right side view of the second embodiment of a container for metal coil;

FIG. 15 is a top elevational view of one interior configuration of the open container for metal coil shown in FIGS. 8-14;

FIG. 16 is a top elevational view of another interior configuration of the open container for metal coil shown in FIGS. 8-14;

FIG. 17 is a top elevational view of yet another interior configuration of the open container for metal coil shown in FIGS. 8-14; and,

FIG. 18 is a top elevational view of a further interior configuration of the open container for metal coil shown in FIGS. 8-14.
